the incident angles of the three electron beams with respect to the color phosphor screen to result in the beams striking different portions of the latter, for example, the screen central portions and the screen boundary portions, at different incident angles and make impossible the provision of uniform brightness over the entire color phosphor screen surface. Conversely, if fine adjustment of the voltage applied to the electron beam deflection means is utilized instead to insure that each of the three beams will strike precisely the proper phosphor stripe on the color phosphor screen, it then becomes impossible to impart satisfactory convergence to the beams through use of this same deflection voltage adjustment.

By this invention is provided a new and improved color picture tube system which, as disclosed herein, is of the three-beam, single-gun type and obviates the above-discussed disadvantages of the prior art systems. More specifically, the color picture tube system of this invention comprises electron beam deflection means which include first and second electron beam deflectors arranged successively between the beam generating cathode and the color phosphor screen. By the use of these first and second electron beam deflectors it is made possible to insure proper convergence of the beams at the screen grid common spot, and proper striking thereby of the color phosphor stripes, while enabling superior electron beam focusing and some measure of cathode ray tube miniaturization. In addition, the three electron beams provided by the beam generating source are caused to pass through the center of the main focussing lens of the single electron gun with one of the beams emerging therefrom along the optical axis thereof, and the other two of the beams emerging therefrom in divergent directions. Subsequently, the other two electron beams are deflected by the respective first and second beam deflectors, which are interposed between the color phosphor screen and the equivalent main lens of the single electron gun, and are caused to converge with the one electron beam at a common spot at a screen grid or mask provided in front of the color phosphor screen, to in turn properly strike the respective color phosphor stripes of the latter and insure excellent picture quality. Since all of the said electron beams are made to pass through the center of the equivalent main lens of the electron gun in the color picture tube system of this invention, the three beams will be substantially free from the influence of coma and/or astigmatism of the said electron gun lens whereby "blurring" of the color phosphor screen beam spots will be substantially prevented.

It is, accordingly, a primary object of this invention to provide a new and improved color picture tube system of the single-gun, plural-beam type having electron beam deflection means which comprise a plurality of successively arranged electron beam deflectors to insure that the plural electron beams will be properly converged to properly strike the different color phosphor stripes of the color phosphor screen throughout the entire extent of the latter.

Another object of this invention is the provision of a single-gun, plural-beam type color picture tube system wherein the electron beams are passed through the optical center of the electron gun main lens to insure that the beams are substantially free from the influence of coma and/or astigmatism of the former and result in the prevention of beam spot "blurring" on the face of the color phosphor screen.

Still another object of this invention is the provision of a single-gun, plural-beam type color picture tube system which is somewhat miniaturized and may be readily manufactured through the use of existing techniques.

The above and other objects and advantages of this invention are believed made clear by the following detailed

This invention relates to a new and improved color picture tube system and, more particularly, to a new and improved single-gun, plural-beam type color picture tube system.

Although single-gun, plural-beam type color picture tube systems are known in the prior art, the inability thereof to maintain the plural beams emitted from the system electron gun properly focussed and converged at the color phosphor screen has been known to give rise to serious operating difficulties. In addition, difficulties have been encountered in preventing the beam spots on the color phosphor screen from becoming "blurred," due to coma and/or astigmatism of the electron gun lens, to result in color picture reproduction of substandard quality.

Preferably, in color picture tube systems of this nature, the distance between the color phosphor screen and the screen, or beam landing position determining, grid or shadow-mask should be relatively short to minimize the axial length of the color picture tube. In addition, it is of significant importance to the provision of high quality, color picture reproduction that a precise relationship in position be maintained between the portion of the screen grid or mask through which the beams pass and the color phosphor stripes of the color phosphor screen. In meeting these requirements, it is preferable that the angle formed by the electron beams at the common spot of convergence thereof at the screen grid or mask be made as large as is possible. This angle can be increased by either increasing the distance between the three electron beams at the surface of the beam generating cathode or by increasing the distance between the main lens of the electron gun and the beam deflection means. Increase in the spacing of the electron beams at the generating surface thereof, however, makes difficult the imparting of a sufficient focussing effect on the beams whereby beam resolution, and accordingly, picture quality, are deteriorated. Similarly, any increase in the main lens deflection means distance is undesirable in that it of course results in increase in the overall length of the color picture tube.

In instances wherein deviations occur in the respective predetermined positions of the screen grid or electron beam deflection means relative to the color screen in single-gun, plural-beam type color picture tube systems, the respective beams will resultantly fail to strike the proper phosphor stripes or dots on the color phosphor screen despite the fact that satisfactory convergence is afforded to the beams by fine adjustment of the deflection voltage applied to the deflection means. Further, such component position deviations will result in variation of

description thereof taken in conjunction with the accompanying drawings wherein

FIG. 1 is a schematic diagram depicting a single-gun, plural-beam type color picture tube system constructed in accordance with the teachings of the prior art;

FIG. 2 is a schematic diagram depicting the optical equivalent or analogy of the tube system of FIG. 1;

FIG. 6 is a schematic diagram depicting still another embodiment of a single-gun, plural-beam type color picture tube system constructed in accordance with the teachings of this invention;

FIG. 7 is an end view which illustrates the magnetic convergence deflector means utilized in the tube system of FIG. 6; and

FIG. 8 is a schematic diagram depicting still another embodiment of the single-gun, plural-beam type color picture tube system constructed in accordance with the teachings of this invention.

To provide for clearer understanding of this invention, a single-gun, plural-beam type color picture tube system of the prior art, wherein use is made of a chromatron type color picture tube of the single-gun, three-beam type, will initially be described with reference to FIGS. 1 and 2. Thus, as seen in FIG. 1, a prior art color picture tube system 10 comprises an electron gun A which includes a cathode K having the electron beam generating sources K_R, K_G and K_B. A first control grid G₁, comprising three grid member G_{1R}, G_{1G}, and G_{1B} is supported in slightly spaced, opposed relationship with the electron-emitting end surface 12 of the cathode K. Apertures g_{1R}, g_{1G} and g_{1B}, are respectively formed as shown in the said grid members, and a common grid G₂ is disposed in the depicted, slightly spaced opposed relationship with the grid G₁. The common grid G₂ comprises apertures g_{2R}, g_{2G}, and g_{2B} formed therein as shown in alignment with the apertures of the said three grid members. The grid G₂ is cup-shaped to include an end plate 14 through which the apertures g_{2R}, g_{2G} and g_{2B} extend at spaced locations on a diametrical line, and a cylindrical portion 16 which extends axially as shown in the direction away from control grid G₁.

Sequentially arranged at axially spaced points in the direction away from the control grid G₁ are open-ended, tubular grids or electrodes G₃, G₄ and G₅, with these electrodes, the control grids G₁ and G₂ and the cathode K being assembled as described by means of suitable, non-illustrated supports of insulating material in the nature, for example, of glass.

In operating the electron gun A of FIG. 1, appropriate voltages are applied to control grids G₁ and G₂ and to the electrodes G₃, G₄ and G₅. Thus, for example, a voltage of 0 to -400 v. may be applied to the three grid members which constitute the control grid G₁, a voltage of 0 to 500 v. may be applied to the control grid G₂, a voltage of 13 to 20 kv. may be applied to the electrodes G₃ and G₅, and a voltage of 0 to 400 v. may be applied to the electrode G₄, all using the voltage of cathode K as the reference voltage. As a result, the respective voltage distributions of the grids G₁ and G₂ and the electrodes G₃, G₄ and G₅, and the respective lengths and diameters thereof, will be substantially identical with those of a unipotential single-beam type electron gun which includes a single, first grid member and a second grid provided with a single aperture.

With the applied voltage distribution as described above, an electron lens field is established between grid G₂ and the end 18 of electrode G₃, and this electron lens field will form the equivalent of an auxiliary lens as indicated in dashed lines at L'. Further, an electron lens field which is the equivalent of a main lens as indicated in dashed lines at L is formed on the axis of electrode G₄ by the electrodes G₃, G₄ and G₅. In one operation of the electron gun A, bias voltages of 100 v., 0 v., 20 kv., 200 v., and 20 kv. are applied to the electrode K, the control grids G₁ and G₂, and the electrodes G₃, G₄ and G₅, respectively.

To effect convergence of the electron beams B_R and B_B which emerge as shown from the electrode G₅ along divergent paths, the electron gun A of FIG. 1 further comprises deflecting means F which include shielding plates P and P', disposed as shown in spaced, opposed relationship, and beam-converging deflector plates Q and Q' which are respectively disposed as shown in spaced, opposed relation to the outer shielding plate surfaces. The shielding plates P and P', and the deflector plates Q and Q', are disposed so that the electron beams B_R, B_G and B_B pass respectively between the plates P and Q, between the plates P and P', and between the plates P' and Q'.

25 A voltage V_P, which is equal to the voltage applied to the electrode G₃, is applied to the deflector plates P and P', and a voltage V_Q, which is lower by 200 v. to 300 v. than the voltage applied to the shielding plates P and P', is applied to the deflector plates Q and Q'. Thus, a voltage difference or deflecting voltage V_C will be applied between the plates P and Q and between the plates P' and Q', respectively, to impart the requisite deflecting action to the electron beams B_R and B_B.

With the system 10 as described, the three electron

35 beams B_R, B_G and B_B will emanate from the cathode K to pass respectively through the grid member apertures g_{1R}, g_{1G}, and g_{1B}, and will be modulated by the "red," "green" and "blue" video signals which are applied between the cathode K and the grid members G_{1R}, G_{1G} and G_{1B}, respectively. The electron beams B_R, B_G and B_B are then passed through the auxiliary lens as indicated at L' and will then intersect each other at the center of the main lens L. Thereafter, the electron beams B_R, B_G and B_B will be passed respectively between the plates Q and P, between the plates P and P', and between the plates P' and Q'.

40 Since plates P and P' are of the same potential, electron beam B_G will not be deflected. The existence of the deflecting voltage V_C will, however, function to deflect electron beam B_R as it passes between the plates P and Q, and to deflect electron beam B_B as it passes between plates P' and Q' whereupon the said electron beams will be directed in the depicted converging manner for impingement of a picture element on the color phosphor screen S.

45 55 The color phosphor screen S is similar to color screens of the chromatron type and is formed by a successive arrangement of sets of "red," "green" and "blue" phosphor stripes S_R, S_G and S_B each of which sets constitutes a color picture element. Spaced as shown from the screen S is a

60 screen grid G_P comprising grid wires g_P pairs of which are disposed as shown in general alignment with the sets of the respective phosphor stripes S_R, S_G and S_B. A relatively high, post-focussing voltage V_M is applied as indicated to the screen grid G_P. The voltage V_M is lower than the 65 voltages applied to the electrodes G₃ and G₅, and the shielding plates P and P', but is sufficiently high, as for example 5 kv. to 7 kv., to operate the grid G_P.

65 The electron beams B_R, B_G and B_B converge as shown at a predetermined angle at a common spot between the two grid wires g_P of a grid wire pair and diverge therefrom in such manner that the electron beam B_R strikes the "red" phosphor stripe S_R, the electron beam B_G strikes the "green" phosphor stripe S_G, and the electron beam B_B strikes the "blue" phosphor stripe S_B. Thus, the said common spot may be understood to correspond to the depicted

set of phosphor stripes. Non-illustrated horizontal and vertical electron beam deflection means would, of course, be provided intermediate the neck portion of the non-illustrated cathode ray tube structure to effect electron beam scanning of the color phosphor screen S in conventional manner. Thus it may be understood whereby the application of the "red," "green" and "blue" color video signals between the cathode K and the grids G_{1R}, G_{1G} and G_{1B}, respectively, will function to intensity modulate the three electron beams B_R, B_G and B_B to result in the provision of a color picture on the color screen S.

In the color tube system 10 of FIG. 1, the electron beams B_R, B_G and B_B are focused by the passage thereof through the center of the main lens L whereby the beams will be substantially unaffected by coma and/or astigmatism of the said main lens to thus substantially prevent the "blurring" of the beam spots on the color phosphor screen S. The distance between the grid G_P and the color phosphor screen S will be predetermined by the axial length of the non-illustrated cathode ray tube face portion. In order to achieve accurate correspondence between the respective grid wire g_P and phosphor stripe set positions, it is desirable that the said predetermined distance be made as small as possible. However, any decrease in this predetermined distance must be accompanied by an increase in the respective incident angles of the electron beams B_R and B_B with respect to the grid G. More specifically, and as now described in detail with reference to the optical analogy diagram of FIG. 2, the following conditions should be satisfied:

$$\frac{D}{d} = \frac{l_1}{l_2}, \quad d = \frac{P_t}{3} \left(l + \frac{l_2 \cdot P_t}{l_1} \right) \therefore l_2 = \frac{l_1 P_t}{3D}$$

wherein l₁ is the distance between the central plane 20 of the deflector means F and the central plane 21 of the grid G_P; l₂ is the distance between the central plane 21 and the color phosphor screen S; d is the width of the respective color phosphor stripes; D is the distance between the points at which the electron beams B_R and B_B pass through the central plane 20 and the point at which the electron beam B_G passes therethrough; and P_t is the distance between adjacent grid wires g_P, otherwise referred to as the screen grid pitch.

Thus, to reduce l₂ or l₁, the distance D must be increased since each of l₂ and l₁ are inversely proportional to D. If l₃ is the distance between the plane 22 of the cathode face 12 and the central plane 23 of the main lens L; l₄ is the distance between the respective central planes 23 and 20; and the angle θ is the angle between either of the electron beams B_R or B_B with respect to electron beam B_G, it then becomes clear that the distance D can only be increased by increasing either of θ or l₄.

Increase of θ will, however, require an increase in the distance U which is the distance on the face 12 of the cathode K between the emission points of either of electron beams B_B or B_R and the emission point of electron beam B_G, and any increase in the distance U will, of course, make more difficult the application of a sufficient and uniform focussing force to all of the electron beams and will give rise to the possibility that the color picture resolution may be deteriorated. Similarly, it is not desirable to increase l₄ since this would require a corresponding increase in the overall length of the non-illustrated cathode ray tube. Further, it is to be understood that any deviation in the distance l₂ from its predetermined value or deviation in the position of the central plane 20 will result, for example, in shifting of the electron beams B_R and B_G to the extent that the same may tend to respectively strike the "green" phosphor stripe S_G or the "red" phosphor stripe S_R of the adjacent phosphor stripe sets with highly disadvantageous result as should be obvious, and this will occur despite adjustment of the convergence voltage which is applied to the convergence deflector means F to provide the possible electron beam convergence. In addition, change in the distance l₂ will

result in corresponding change in the incident angle of each of the electron beams at the central plane 21 of the grip G_P whereby the position where each of the electron beams strikes the color phosphor screen S will be shifted and the conditions under which the respective beams strike the color phosphor screen S will be different in the upper and lower end portions of the cathode ray tube than they are in the central portions of the latter. Conversely, if the voltage applied to the convergence deflector means F is finely adjusted to prevent shifting of the electron beam striking positions on the color phosphor screen S, it then becomes impossible to achieve proper convergence of the electron beams in the central portions of the screen. It therefore becomes most difficult to simultaneously achieve proper convergence of the electron beams B_R, B_G and B_B and proper striking of the said electron beams on the respective color phosphor stripe sets.

In accordance with this invention there is provided a new and improved color picture tube system which is capable of effectively solving the aforementioned problems as arise in the operation of the color picture tube systems of the prior art.

Referring now to FIG. 3, there is shown therein an embodiment of the color picture tube system of this invention, as indicated generally at 30, which includes a chromatron type color picture tube of the single-gun, three-beam type as described hereinabove with regard to the prior art color tube system of FIG. 1. In the system 30 of FIG. 3, the electron gun is indicated generally at A₁ and has a construction similar to that of the electron gun A of FIG. 1. Accordingly, corresponding parts will be identified with corresponding reference symbols whereby it may be understood that electron gun A₁ comprises, in the manner of electron gun A, a cathode K, control grids G₁ and G₂, and electrodes G₃, G₄ and G₅.

Voltages, based as before on the cathode voltages, which are equal to those described with reference to FIG. 1 are applied to the control grids G₁ and G₂ and the electrodes G₃, G₄ and G₅ of the electron gun A₁ whereby the electron beams B_R, B_G and B_B which emanate from the gun cathode K are passed through apertures g_{1R}, g_{1G}, and g_{1B} of the control grid G₁, apertures g_{2R}, g_{2G} and g_{2B} of the control grid G₂, and then through the auxiliary lens L' by which the electron beams are converged at the optical center of the main lens L with the electron beams B_R and B_B emerging from the latter as before along divergent paths.

Included in the deflecting means F₁ of FIG. 3 are spaced electrode plates P and P' between which the electron beam B_G will pass. At the electron gun side of the electrode plates P and P', electrode plates Q₁ and Q'₁ are disposed as shown in spaced, opposed relationship with the outer faces of the electrode plates P and P'. Thus, the electron beams B_B and B_R will pass respectively between the electrode plates P and Q₁ and the electrode plates P' and Q'₁. Plates H and H' are disposed as shown adjacent the respective electrode plates P and P' in opposed relationship with the outer faces of the latter, and electrode plates Q₂ and Q'₂ are in turn disposed as shown in spaced manner from the outer faces of the plates H and H' and in opposed relationship therewith. Thus, the electron beams B_R and B_B will pass respectively between the plates H and Q₂ and between the plates H' and Q'₂. In this instance, the axial extent of the electrode plates Q₂ and Q'₂ is made greater than the axial extent of the electrode plates Q₁ and Q'₁. Preferably, the electrode plates P and P' are bent as shown so that the space therebetween increases gradually in the direction of the color phosphor screen S over a distance which extends from the area of the screen-side edges of the electrode plates Q₁ and Q'₁ to the central area of the plates H and H'. In similar manner, the respective plates H and H' and Q₂ and Q'₂ are bent so as to maintain the respective inner faces thereof substantially parallel with the respec-

tive outer faces of electrode plates P and P'. This bending of the respective plates may, however, be rendered unnecessary by increase in the respective spacing therebetween.

The electrode plates P, P', Q₂ and Q'₂ are electrically connected as shown to terminal T_P to which is applied a voltage V_P which is equal to the voltages applied to the electrodes G₃ and G₅ and will thus range from 13 kv. to 20 kv. In like manner, the plates H, H', Q₁, and Q'₁ are electrically connected and coupled to a terminal T_Q to which is applied a voltage V' which exceeds the voltage V_P by a voltage V_C ranging from 200 v. to 300 v. To this effect, an equivalent convergence deflecting voltage source VS is connected as shown across the terminals T_P and T_Q.

As a result of the above, it may be understood that the deflecting means F₁ will include a first deflector f₁ as constituted by the electrode plates P and P', P and Q₁, and P' and Q'₁, and a second deflector f₂ as constituted by the electrode plates P and P', H and Q₂ and H' and Q'₂. The respective first and second deflectors f₁ and f₂ are successively arranged as shown in the paths of the electron beams B_R, B_G and B_B. Thus, the electron beams B_R and B_B will pass respectively between the plates P and Q₁ and between the plates P' and Q'₁ and will be deflected in divergent directions by the first deflector f₁. Thereafter, in passing respectively between the electrode plates H and Q₂ and between the electrode plates H' and Q'₂, the electron beams B_R and B_B will be deflected in convergent directions by the second deflector f₂.

In this embodiment of my invention, the axial extent of the first deflector f₁ is made greater than the axial extent of the second deflector f₂, and a difference in deflection sensitivity is provided therebetween so that the electron beams B_R, B_G and B_B may again be converged at the common spot at the grid G_P. Thus it may be understood that by the application of "red," "green" and "blue" color video signals between the cathode K and the grid G₁ respectively, the three electron beams B_R, B_G and B_B will be intensity modulated, whereby a color picture is provided on the color phosphor screen S.

As indicated in the optical equivalent or analogy diagram of FIG. 4, the distance l₂ is measured between the central plane 21 of the grid G_P and the color phosphor screen S, the distance l is measured between the face 12 of the cathode K and the central plane 23 of the main lens L, the distance (l₄+l₁) is measured between the respective central planes 23 and 21, and the distance d is the width of one of the color phosphor stripes, with all of these distances being equal to the correspondingly identified distances in the optical analogy or equivalent diagram of the FIGURE 2. Accordingly, the angle θ' between the respective electron beams prior to the incidence thereof on the central plane 24 of the first deflector f₁ may be smaller than the corresponding electron beam angle θ of FIG. 2 whereupon the distance U' between the respective electron beams on the face 12 of the cathode K may be made smaller than the distance U of FIG. 2. Accordingly, the lens system of the electron gun 30 of FIG. 3 may be understood to apply a more uniform focussing action to the respective electron beams B_R, B_G and B_B than does the prior art electron gun 10 of FIG. 1. As a result, significant improvement in the resolution of the color picture produced on the color phosphor screen S of FIG. 3 is made possible.

In addition, the distance D' in FIG. 4 as measured between the incidence points of the respective electron beams on the central plane 25 of the second deflecting means f₂ also becomes smaller than the similarly measured distance D of FIG. 1 whereby a more linear deflecting action for enabling the three electron beams to horizontally and vertically scan the color phosphor screen S will be imparted to the three electron beams which are, of course, subjected to the horizontal and vertical deflec-

tion action of the non-illustrated horizontal and vertical deflection coils after having passed through the second deflector f₂. Consequently, it becomes possible to effectively prevent any distortion of the picture produced on the said color phosphor screen.

Alternatively, by arranging the system of FIG. 3 to make the electron beam angle θ' of FIG. 4 equal to the electron beam angle θ of FIG. 2, it becomes possible to reduce the overall cathode ray tube length by an amount corresponding to the difference between θ' as indicated in FIG. 4 and θ as indicated in FIG. 2, to thus provide for some measure of miniaturization of the cathode ray tube.

Since the respective first and second deflectors f₁ and f₂ of the system 30 of FIG. 3 can be operated through the use of the voltages applied to the terminals T_P and T_Q, the power supply circuit for the said deflecting means will not be unduly complicated.

Although no description has been made in the foregoing 20 of the application of a horizontal dynamic converging effect to the respective electron beams B_R, B_G and B_B, it is to be understood that such effect can readily be applied through the incorporation in the convergence deflecting voltage source VS of FIG. 3, well known means for providing a parabolic wave form voltage in addition to the power supply means which produce the static convergence deflecting voltage V_C.

As described hereinabove, the electrode plates Q₁, Q'₁, H and H' are electrically connected with each other and 30 coupled to the terminal T_Q. Alternatively, it is of course possible to separately connect electrode plates Q₁ and H to provide a first terminal, to separately connect electrode plates Q₁ and H to provide another terminal, and to separately apply deflecting voltages to the said terminals to thereby compensate for the slight unbalance of the side electron beams B_R and B_B with respect to the center electron beam B_G.

In the system embodiment 40 of FIG. 5, the electron gun is indicated generally at A₂, the deflecting means at 40 f₂, the screen grid at G_P, and the color phosphor screen at S, and the respective components thereof which are the same as the respective components of the embodiments of FIGS. 1 and 3 again bear the same identifying reference characters. As illustrated in FIG. 5, the convergence deflecting means f₂ again comprise first and second deflectors as indicated at f₃ and f₄. The deflecting means f₃ include spaced electrode plates Q₁ and Q'₁ which are positioned as shown in opposed relationship with the outer surfaces of electrode plates P and P' which are common to both of the said deflecting means. The deflector f₄ comprises electrode plates Q₂ and Q'₂ spaced as shown, and electrode plates H and H' which are disposed on the outer surfaces of the electrode plates P and P', through the use of insulating material layers I and I', in opposed relationship with the inner surfaces of the electrode plates Q₂ and Q'₂. Thus, upon leaving the electrode gun A, the central electron beam B_G will pass substantially undeflected between the electrode plates P and P', while the one side electron beam B_B will pass 55 between electrode plates B' and Q'₁ and between the electrode plates H' and Q'₂, and the other side electron beam B_R will pass in turn between electrode plates P and Q₁ and electrode plates H and Q₂, respectively.

The electrode plates P and P' and Q₂ and Q'₂ are connected as indicated to a terminal T_P to which is applied to voltage V. The electrode plates Q₁, Q'₁, H and H' are coupled to a terminal T and a voltage V₂ from a power source VS is applied to the terminal T₂ with the said voltage being equivalent to the voltage V_C as described 60 hereinabove with regard to the embodiment of FIG. 3. Thus, in the system of FIG. 5, the electron beams B_R and B_B will, in passing between the respective electrode plates P and Q₁ and P' and Q'₁, be deflected in divergent directions by the first deflector f₃. Then, and in passing respectively between the electrode plates H and Q₂ and

between the electrode plates H' and Q'_2 of the second deflector f_4 , the electron beams B_B and B_R will be deflected in convergent directions to thus result in electron beam convergence as shown at the common spot at the screen grid G_p . As discussed hereinabove with regard to the embodiment of FIG. 3, it is believed readily apparent a horizontal dynamic convergence effect could be provided in the embodiment of FIG. 5 through the provision therein of a horizontal dynamic convergence voltage generating means.

In the embodiment of FIG. 6 the color tube system is indicated generally at 50, the electron gun is indicated at A_3 , the electron beam deflecting means at F_3 , the screen grid at G_p , and the color phosphor screen at S , and the same components thereof again bear the same reference characters. The embodiment of FIG. 6 differs from the embodiment of FIGS. 3 and 5 in that the deflecting means F_3 of the former are of the magnetic, rather than the electrostatic, type. Thus, as seen in FIGS. 6 and 7, the deflecting means F_3 include a magnetic shield member T which extends, in the manner of the spaced electrode plates P and P' of FIG. 5, to be common to both of the first deflector, as indicated at f_5 , second deflector, as indicated at f_6 . As best seen in FIG. 7, the magnetic shield member T is of generally rectangular configuration and is defined respectively by right and left side wall plates 31 and 31', and by upper and lower plates 32 and 32'. In operation, the central electron beam B_G passes through the magnetic shield member T without being magnetically deflected.

Since the deflecting means F_3 are of generally symmetrical construction in both of the axial and transverse directions, and in the interests of avoiding unnecessary duplication of drawings, each of FIGS. 6 and 7 will be seen to include, in many instances, a second set of component reference characters placed in parentheses and it is to be understood that this parenthesized second set of reference characters indicates a substantially identical component which lies directly behind the depicted component in each instance. Thus, as seen in FIGS. 6 and 7, at the electron gun side of the magnetic shield member T there is provided a magnetic pole piece member M_{11} comprising a magnetic plate 33a extending substantially perpendicularly with respect to the side wall plate 31, and a magnetic plate 34a which is bent in such manner as to extend along the annular inner surface of the cathode ray tube neck portion, as indicated in broken lines at N , upwardly from the outer end of the magnetic plate 33a. Also provided at the electron gun side of the magnetic shield member T are a magnetic pole piece member M_{12} which comprises a magnetic plate 33b disposed in opposition to the magnetic plate 33a, and a magnetic plate 34b which is bent in such manner as to extend along the inner surface of the cathode ray tube neck portion N downwardly from the outer end of the magnetic plate 33b. In addition, and again at the electron gun side of the magnetic shield member T is provided a magnetic pole piece member M'_{11} which is configured in the same shape as the magnetic pole piece member M_{11} and comprises a magnetic plate 33a' and a magnetic plate 34a' extending therefrom. A magnetic pole piece member M'_{12} configured in the same shape as the magnetic pole piece member M_{12} is also provided and comprises a magnetic plate 33b' and a magnetic plate 34b' extending therefrom. As best seen in FIG. 7, the respective magnetic pole piece members M_{11} , M_{12} , M'_{11} and M'_{12} are symmetrically disposed around the magnetic shield member T in mutually opposed relationship.

At the color phosphor screen side of the magnetic shield member T , magnetic pole members M_{21} and M_{22} , configured in the same shape as the magnetic pole members M_{11} and M_{12} , are provided adjacent the side wall plate 31 of the said magnetic shield member; and magnetic pole members M'_{21} and M'_{22} , configured respectively in the same shapes as the magnetic pole members M'_{11} and M'_{12} , are provided adjacent the side wall plate 31' of the

magnetic shield member T . An annular electromagnet C_1 is provided around a part of cathode ray tube neck portion N and consists of a core 36 having a magnetic pole 35a disposed in opposed relationship with the plate 34a of the magnetic pole member M_{11} , and a magnetic pole 35b disposed in opposed relationship with the plate 34b of the magnetic pole member M_{12} , and a winding 37 which is wound as indicated on the core 36. In like manner, an annular electromagnet C'_1 is disposed to the other side of the said tube neck portion, and the former consists of a core 36' having magnetic poles 35a' and 35b' disposed in opposed relationship with the plate 34a' of the magnetic pole member M'_{11} and the plate 34b' of the magnetic pole member M'_{12} , respectively, and a winding 37' which is wound as shown on the core 36'.

Disposed around the neck portion end to the screen side thereof, is an annular electromagnet C_2 which consists of a core having magnetic poles disposed in opposed relationship with the plate 34a of the magnetic pole piece member M_{21} and the plate 34b' of the magnetic pole piece member M_{22} , and a winding 37a is wound around this core. An annular electromagnet C'_2 is provided around a part of the neck portion to the screen side of the latter and consists of a core having magnetic poles disposed in opposed relationship to the plate 34a' of the magnetic pole piece member M'_{21} and the plate 34b' of the magnetic pole piece member M'_{22} , and a winding 37a' is wound around this core.

In operation, and upon leaving the electron gun A_3 as seen in FIG. 6, the electron beam B_B will pass undeflected through the magnetic shield member T . The electron beam B_B will pass between the plate 33a of the magnetic pole piece member M_{11} and the plate 33b of the magnetic pole piece member M_{12} , and will then pass between the plate 33a of the magnetic pole piece member M_{21} and the plate 33b of the magnetic pole piece member M_{22} . In like manner, the beam B_R will pass between the plates 33a' and 33b' of the respective pole piece members M'_{11} and M'_{12} , and will then pass between the plates 33a' and 33b' of the respective magnetic pole members M'_{21} and M'_{22} . Thus it is believed made clear whereby electromagnetic deflecting means f_5 which are functionally equivalent to the respective electrostatic deflectors f_1 and f_3 as described hereinabove with reference to the embodiments of FIGS. 3 and 5, will be constituted by the magnetic pole piece members M_{11} , M_{12} , M'_{11} and M'_{12} , electromagnets C_1 and C'_1 , and magnetic shield member T . In like manner, electromagnetic deflectors f_6 which are the equivalent of the respective electrostatic deflectors f_2 and f_4 as described hereinabove with regard to the embodiments of FIGS. 3 and 5, will be formed by the magnetic pole members M_{21} , M_{22} , M'_{21} and M'_{22} , electromagnets C_2 and C'_2 , and the magnetic shield member T .

A deflecting current is supplied from an external source to the winding 37 of the electromagnet C_1 to result in the formation of a proportional magnetic field and the passage of the latter through the magnetic pole members M_{11} and M_{12} to apply the requisite deflecting action to the electron beam B_B . In this instance, the current is applied to the electromagnet winding 37 in such direction as to effect the divergent deflection of the electron beam B_B in its passage between the plates 33a and 33b. In like manner, a deflecting current of the same magnitude is applied to the winding 37' of the electromagnet C'_1 to provide the requisite magnetic field through the magnetic pole members M'_{11} and M'_{12} to impart the requisite divergent deflection to the electron beam B_R .

Deflecting currents likewise applied to the windings 37 and 37' of the respective electromagnets C_2 and C'_2 to effect the subsequent, convergent deflection of the electron beams B_B and B_R , it being noted, however, that the deflecting current flow directions in the respective windings 37 and 37' will, of course, be opposite to those in the windings of the electromagnets C_1 and C'_1 to insure that the respective electron beams B_B and B_R are convergently de-

flected by the deflector f_6 . Thus the electron beams B_R , B_G and B_B will again be converged at the common spot at the screen grid G_P . Again, as was the case with the embodiments of FIGS. 3 and 5, horizontal dynamic convergence may be effected in the embodiment of FIG. 6 through the provision of a suitable dynamic convergence current to the windings of the respective electromagnets C_1 , C'_1 , C_2 and C'_2 .

In the embodiment of FIG. 8 the color tube system is indicated generally at 60 and comprises an electron gun as indicated at A_4 , the electron beam deflecting means as indicated at F_4 , a screen grid as indicated at G_P , and a color phosphor screen as indicated at S , with like components again being identified by like reference characters. Comparison between the embodiment of FIG. 5 and the embodiment of FIG. 8 will make clear that, in the latter, the deflecting means F_4 include first and second deflectors f_7 and f_8 which are constituted by spaced electrode plates P and P' , Q_1 and Q'_1 , Q_2 and Q'_2 and do not, as in the embodiment of FIG. 5, include the additional electrode plates H and H' and their associated insulators I and I' . Too, in the embodiment of FIG. 8, the electrode plates Q_2 and Q'_2 are connected as shown to a terminal T_R rather than to the terminal T_P as heretofore.

A voltage V_R which is either substantially equal to or lower than the voltage V' (FIGURE 5) is applied to the terminal T_R from an equivalent power source VS' which is similar to the power source VS . The power source VS' is connected as shown across the terminals T_P and T_R to effect the static deflection of the respective electron beams B_R and B_R in convergent directions in both of the first deflector f_7 and the second deflector f_8 . In this instance, conventional horizontal dynamic convergence voltage generating means may be understood to be incorporated in the equivalent power sources VS and VS' .

With the system of FIG. 8, the voltage V'_Q and/or the voltage V_R are adjustable, through the adjustment of either one of the equivalent power sources VS and VS' , to enable the correction of the position of the apparent deflection center of the deflection means F to a predetermined position with respect to the respective electron beams B_R and B_R . By the system of FIG. 8, it also becomes possible to correct the incident angles of the electron beams B_R , B_G and B_B at the common spot with respect to the screen grid G_P . Thus, if the distance between the color phosphor screen S and the screen grid G_P and/or the distance between the latter and the deflecting means F are somewhat deviated, it is nonetheless possible to compensate for the resultant misconvergence of the electron beams B_R , B_G and B_B at the screen grid G_P to insure that the said electron beams properly strike the respective color phosphor stripes S_R , S_Q and S_B .

Suitable modification could, of course, be made in the embodiment of FIG. 8 to achieve therein convergent, rather than divergent, deflection of the respective electron beams B_R and B_R in the first deflector f_8 in the manner described hereinabove with regard to the embodiments of FIGS. 3 and 5. Too, and with regard to the embodiment of FIG. 6, it is to be understood that the respective current flow directions of the deflecting currents supplied to the electromagnets C_1 and C'_1 of the first deflector f_5 may be arranged to be opposite to those described above to thus provide for the convergent deflection of the said electron means in both of the first deflector f_5 and the second deflector f_6 of the embodiment of FIG. 6.

Further, it is to be understood that three electrically independent cathodes may, in each of the disclosed embodiments of this invention, be substituted for the single cathode K . In addition, although the first grid G_1 of the electron gun has in each instance been described as being formed by electrically independent grid members G_{1R} , G_{1G} , and G_{1B} , it is also to be understood that a single grid member comprising three apertures may be readily substituted therefor. Similarly, it is believed apparent that the herein disclosed embodiments of this invention would

all be equally applicable to a color picture tube system utilizing a conventional shadow-mask type color picture tube wherein the screen grid G were replaced by a shadow-mask. Also, although disclosed herein as applied to a three-beam color picture tube, it is to be understood equally applicable, with suitable modification, to use in conjunction with color picture tubes wherein two electron beams, or four or more electron beams, are utilized in the reproduction of color pictures.

It will be apparent that many modifications and variations other than those described hereinabove, may be effected in the disclosed embodiments of this invention without departing from the spirit and scope of the latter as defined by the appended claims.

What is claimed is:

1. In a color picture tube system which includes a color screen, an electron gun means spaced therefrom, means for directing a plurality of electron beams toward said color screen, lens means for focussing said electron beams, and means for passing said electron beams through the optical center of said focussing lens means with one of said beams emerging therefrom along the optical axis of said focussing lens means and the other of said beams emerging therefrom along paths which are divergent thereto, the improvements comprising, electron beam deflecting means including first and second electron beam deflectors which are arranged successively in the path of said electron beams from said electron gun means to said color screen, said electron beam deflecting means being operable to enable the undeflected passage therethrough of said one beam while deflecting said other beams so that all of said electron beams may be converged at a common spot corresponding to a color picture element on said color screen.
2. In a color picture tube system as in claim 1 wherein, said first electron beam deflector deflects said other electron beams in divergent manner, and said second electron beam deflector deflects said other electron beams in convergent manner to achieve said electron beam convergence at said common spot.
3. In a color picture tube system as in claim 1 wherein, said first electron beam deflector deflects said other electron beams in convergent manner, and said second electron beam deflector also deflects said other electron beams in convergent manner to thereby effect said electron beam convergence at said common spot.
4. In a color picture tube system as in claim 1 wherein, each of said first and second electron beam deflectors comprises means for applying an electric field to said other electron beams to thus electrostatically deflect said other electron beams.
5. In a color picture tube system as in claim 1 wherein, each of said first and second electron beam deflectors comprises means for applying a magnetic field to said other electron beams whereby the latter are magnetically deflected.
6. In a color picture tube system as in claim 2 wherein, each of said first and second electron beam deflectors includes means for applying an electric field to said other electron beams whereby, said other electron beams are electrostatically deflected.
7. In a color picture tube system as in claim 2 wherein, each of said first and second electron beam deflectors includes means for applying a magnetic field to said other electron beams whereby said other electron beams are magnetically deflected.
8. In a color picture tube system as in claim 3 wherein, each of said first and second electron beam deflectors includes means for applying an electric field to said other electron beams whereby, said other electron beams are electrostatically deflected.
9. In a color picture tube system as in claim 6 wherein, said first and second electron beam deflectors comprise an adjustable deflecting voltage source connected thereto whereby, the extent of said other electron beam

deflections may be controlled by adjustment of said adjustable deflecting voltage source.

10. In a color picture tube system as in claim 7 wherein, said first and second electron beam deflectors comprise an adjustable deflecting current source connected thereto whereby, the extent of said other electron beam deflections may be adjusted by adjustment of said adjustable deflecting current source.

11. In a color picture tube system as in claim 8 wherein, said first and second electron beam deflectors comprise an adjustable deflecting voltage source connected thereto whereby, the extent of said electrostatic deflection of said other electron beams may be adjusted by adjustment of said adjustable deflecting voltage source.

12. In a color picture tube system as in claim 8 wherein, said first electron beam deflector comprises an adjustable deflecting voltage source connected thereto, and said second electron beam deflector comprises another

5

10

15

adjustable voltage source connected thereto whereby, the respective electrostatic deflections of said other electron beams may be adjusted by adjustment of said adjustable voltage source and said another adjustable voltage source, respectively.
